UNITED STATES PATENT OFFICE.

GEORGE WALD, OF WASHINGTON, DISTRICT OF COLUMBIA.

PHOTOGRAPHIC APPARATUS.

1,405,080.

Specification of Letters Patent. Patented Jan. 31, 1922.

Application filed October 10, 1919. Serial No. 329,842.

To all whom it may concern:

Be it known that I, GEORGE WALD, a citizen of the United States, residing at Washington, in the District of Columbia, have 5 invented certain new and useful Improvements in Photographic Apparatus, of which the following is a specification.

The object of my invention is to enable an operator to expose, print and develop 10 photographs in day light without the use of a dark room.

Referring to the drawings which illustrate the devices used to accomplish the above results.

15 Figure 1 is a cross sectional side view of the device;

Figure 2 is a top view of the exposing box, with all of top cover removed except that part holding the glass through which 20 the light passes;

Figures 3, 4 and 5 show the devices used to engage and disengage the friction cones;

Figures 6, 7 and 8 illustrate the methods used in adjusting the exposing space to correspond to the strengths of lights;

Figure 9 shows a split-ring;

Figure 10 shows a film after being developed; and

Figure 11 shows a strip of paper similar to film 10 on which the photograph is printed by exposure to light.

Similar parts are designated by similar numbers.

The operation of my invention is as follows:

The film or negative after being developed is in one strip, at each end of which is pasted on two strips of paper four or five feet long and of the same width as the film.

40 This film (Fig. 10) is wound up on the same spool on which the films are generally rolled in the market. A similar strip of paper, Fig. 11, of corresponding length and width as the film is to be made with the center part (somewhat longer than the film proper) properly sensitized, is wound upon a similar spool. The end of the paper strip is to be red so as to prevent light rays penetrating the sensitized paper beneath. Both

50 spools are secured in place in a light-tight box so as to allow the rotation of same. Both ends of these strips (film and printing paper) are secured on a third spool on which they are wound up while exposed to light. After the paper and film receive the light exposure, the light rays are shut off

and the strips returned and again wound on their respective spools. The box is then opened, the exposed paper removed as it is wound on the spool and then developed. 60

I will now explain fully my apparatus for printing photographs in day light.

Referring to Figure 1, 1 is a box in the top 1^a is an opening in which the ground glass 2 is secured by a metal frame 3. The box 1 has a light-tight partition in it 1^b. Between 1^b and 1^c (see Fig. 2) are secured two partitions 4 and 5, sloping downwards (see Fig. 1), both terminating in rollers which are in contact with the spring-metal 70 surface 6 which is in turn secured to the legs or holders 7 secured to the bottom 1^d of the box 1. The bottom 1^d is opened and with it 7 and 6 are removed from the rollers 10, 10, and the rollers 4' and 5' in 4 and 5. The 75 bottom is now pulled outwards and the spool 9 on which is wound the photographic paper 8 is inserted between the two friction points of shafts 12 and 13. The bottom 11 is pushed back in until the friction points engage the 80 hole in the spool so as to allow the spool 9 to rotate when the paper 8 is pulled. The shaft 12 is held in place by the slots or depressions 14 grasped in the spring ring 15 (shown in Fig. 9), which in turn is held in 85 the pressed steel holder 16, against the wall 1^c. A number of slots 14 are provided in the shaft 12 so as to allow any width of paper and spool corresponding to any standard film size to be used. The slot in the wood 90 body of the commercial spool used, engages the shoulders 17 of piece 18 against which the wheel of the spool 9 rests, in such a manner that the shaft 13 rotates with the spool 9 while shaft 12 remains standing still. The 95 cone 19 which is mounted on the shaft 13 and rotating when the latter rotates, is normally not engaged and therefore free to rotate. Sufficient of the paper strip 8 is pulled off to reach the spool 20, which paper is temporarily bent toward the hinge 21 while the bottom 14 is open. The spool 22 is held by a similar arrangement to that of spool 9. It holds the film 23 (see Fig. 10). The paper ends of both film 23 and paper 8 are pushed 100 through the slot 24 in the spool 20, (see Fig. 1). The spool 20 is secured solidly to shaft 25 which is turned by crank and handle 26 and 27, respectively. The handle 27 is now turned a turn or two, thus securing tightly 110 the end papers of film 23 and sensitized paper 8 on the spool 20. The bottom 1^d is now

closed and held tight by catch 29 on pin 30. The angular seam between box 1 and bottom 1^a prevents the rays of light from entering the box 1, more so as the weight of the box 5 1 rests on the bottom 1^a. The handle 27 is now rotated with a fair constant speed till the entire film and paper rolls are wound up on the spool 20. The end 31 of film 23 and end 32 (right-hand side Fig. 11) of paper 8 10 are secured to their respective spools 22 and 9 by a paster so as not to make it necessary at this time to reopen the box. In order to attain a constant speed of spool 20 while same is rotated by handle 27, a fly-wheel 33 15 is mounted on a shaft 34 on which latter is also mounted a large gear wheel 35 in mesh with a small gear wheel 36 mounted in turn on shaft 25. Thus with a fairly constant rotation of crank handle 27, a constant speed 20 of the spool 20 will be maintained. The body 25 of the spool 20 is of large diameter so that the increase in the latter diameter will not cause much difference in the speed of the film 23 and paper 8, while same are passing by the opening 37. The light rays passing 30 through the window 2 and through the film, act on the chemicals of the sensitized paper 8. Both film 23 and paper 8 are held tight together by the pull of same while winding on spool 20 and by the rollers 4' and 5' in partitions 4, 5 and 10—10 against the smooth surface of the spring plate 6. In order to provide for bright and dark days a hinged partition 38 is hinged at 41 extending the entire 35 width between wall 12 and 1^a. The end of 40 38 has secured to it a stiff cloth edging 40. This partition 38 swinging on its point 41 away from 4 will increase the opening 37 until the maximum point is reached, beyond 45 which the cloth 40 will rise from the film surface on spring plate 6. If 38 is swung in the opposite direction toward the partition 4 the cloth 40 will touch partition 5 and the entire opening 37 will be closed up, excluding 50 all light from the film 23 and paper 8. The ends of 38 against 1^b and 1^c can also be fixed with cloth edging like that of 40 so as to allow 38 to swing easily between walls 1^b and 1^c, and still be light-tight. 55 Normally flat spring 39 pushes 38 away from 4. Rod 42 is pivoted at one end to 38 and the other end to shaft 43 through link connection 44. Shaft 43 is supported in bracket 45 secured to 4 and in the walls 1^b and 1^c. Shaft 43 may either be a solid piece with shaft 46 or for ease in construction, 46 may terminate in a sleeve and slot arrangement 47 engaging pin 48 secured in shaft 43 (see Figs. 6, 7 and 8). As knob 60 49 is rotated, 38 is pulled toward 4 or is pushed away from same. On shaft 46 is mounted a ring washer 50 terminating in a sleeve in which a pin 51 is held against a spring. The other end of 51 has a roller 52 65 held against the half ring washer 53 by

notches or depressions 54 (see Fig. 6). This arrangement permits hinged partition 38 to be held in forms in four positions, viz., R, B, F, and D, Fig. 7. The position of Fig. 1 being B or bright light, F indicates the 70 fair light position and D the dark position. From B to D, 38 would move from the position shown in Fig. 1 to a point right up against 4.

It is absolutely necessary that the light 75 rays be shut off from the sensitive paper 8 when same is rewound on its spool 9. To accomplish this the shaft 46 is turned by knob 49 to the position R when the light rays are entirely shut off. 80

As said before, spool 9 revolves together with shaft 13, the latter being free to revolve as cone 19 is not engaged. Likewise spool 22 revolves with shaft 55 on which is mounted cone 56 (see Fig. 5). 85

Shaft 57 is secured in wall 1^e and may be turned by crank 58 and handle 59. On wall 1^e is secured piece 60. A rod 61 of the shape as shown in Figs. 3 and 4 having a slot 62 is slidably mounted on shaft 57 90 between piece 60 and cone 64. The rod 61 ends in a wedge like end 63 so that when the latter is pulled in between 60 and 64, the cone 64 is pushed against spring 65 and causes 64 to engage frictionally cones 19 and 56. The spring 65 is held against washer 66 secured by a pin to shaft 57. The cone 64 is slidably mounted on the shaft 57 but through a key and slot arrangement is made to revolve with shaft 57. The rod 61 (see Fig. 2) is pivoted 100 to link 67, the latter in turn secured to shaft 46. As the knob 49 is turned from B to D the rod 61 slides between 60 and 64 on the flat portion thereof (right-hand side Figs. 3 and 4). However, if the position R is reached the wedge-shape 63 is pulled between 60 and 64 and the cone 64 engages 19 and 56, thus the film 23 and paper 8 can be rewound on their respective spools 22 and 9, 58 and 59. At this time, however, the opening 37 is 110 closed light-tight. The positions R, B, F and D shown in Fig. 7 are marked on either the wall 1^e or on the cover 68 covering the devices shown in Fig. 6. A pointer 69 secured to shaft 46 indicating the proper position of 115 38. The sensitized part, SP, of the paper 8 is to be longer than the film part PP, of the film strip 23 so as to ensure proper action.

End 32 (left hand side Fig. 11), of paper 8 must be of a non-actinic color so as to 120 prevent light rays penetrating SP.

Commercially the ends 31 can be wound on top of the spool containing paper 8 and fixed with glue to be pasted to film 23.

I claim:

1. A photographic printing apparatus including a light tight casing having an opening, a film negative supply roll, a sensitized paper supply roll, a take up roll common to both of the rolls aforesaid, means for rotat- 130

ing the said take up roll, and a transversely arranged shutter for admitting light to the interior of said apparatus through the aforesaid opening during passage of negative and 5 paper strips from said supply to said take up rolls.

2. A photographic printing apparatus including a light tight casing having an opening, a film negative supply roll, a sensitized 10 paper supply roll, a take up roll common to both of the rolls aforesaid, means for rotating the said take up roll, and a transversely arranged adjustable shutter for admitting a light streak of variable widths to 15 the interior of said apparatus through the aforesaid opening and during passage of negative and paper strips from said supply to said take up rolls.

3. A photographic printing apparatus including a light tight casing having an opening, a film negative supply roll, a sensitized paper supply roll, a take up roll common to both of the rolls aforesaid, means for rotating the said take up roll, a downwardly converging light duct communicating with the aforesaid opening and leading into the apparatus, and a movable shutter for admitting light to the interior of said apparatus through the aforesaid opening during the 30 passage of the negative and paper strips from said supply rolls to said take up roll.

4. A photographic printing apparatus including a light tight casing having an opening, a film negative supply roll, a sensitized 35 paper supply roll, a take up roll common to both of the rolls aforesaid, means for rotating the said take up roll, a transversely arranged adjustable shutter for admitting light streaks of variable widths to interior 40 of the apparatus, and means for actuating said shutter.

5. In photographic printing apparatus including a light tight casing having an opening, with a film negative supply roll, a sensitized 45 paper supply roll, a take up roll common to both of the rolls aforesaid, means for rotating the said take up roll, a transversely arranged adjustable shutter for admitting light streaks of variable widths to interior 50 of the apparatus through the aforesaid opening, and graduated means for actuating said shutter from the exterior of the apparatus.

6. A photographic printing apparatus including a light tight casing having an opening, 55 a film negative supply roll, a sensitized paper supply roll, a take up roll common to both of the rolls aforesaid, means for rotating the said take up roll, a balance wheel operatively connected with a shaft carrying 60 said take up roll, and a transversely arranged adjustable shutter for admitting light through the aforesaid opening to the interior of the apparatus in varying degrees of intensity. 65

7. A photographic printing apparatus including a light tight casing having an opening, a film negative supply roll, a sensitized paper supply roll, a take up roll common to both of the rolls aforesaid, means for rotating 70 the said take up roll, a transversely arranged adjustable shutter for admitting light to the interior of the apparatus through the aforesaid opening in varying degrees of intensity, means for actuating said shutter 75 from the exterior of the apparatus, and means for automatically retaining the shutter in its adjusted positions.

8. A photographic printing apparatus including a light tight casing having an opening 80 therein, a shutter for said opening, a film negative supply roll, a sensitized paper supply roll, a take up roll common to both of the rolls aforesaid, means for rotating the said take up roll, and means for simultaneously rewinding said supply rolls including a driven gear on each roll-supporting shaft, an intermediate driving gear normally out of engagement but adapted to engage the aforesaid gears when occasion requires, and a crank for rotating said driving gear during the rewinding operation. 85

9. A photographic printing apparatus including a light tight casing having an opening, a film negative supply roll, a sensitized 95 paper supply roll, a take up roll common to both of the rolls aforesaid, means for rotating the said take up roll, and means for rewinding said supply rolls and means operated by the said rewinding means for covering 100 the aforesaid opening for automatically excluding light from the interior of the apparatus during the rewinding operation.

In testimony whereof I affix my signature.

GEORGE WALD.
